(57) **CLAIM**

The ornamental design for a camera, as shown and described.

DESCRIPTION

FIG. 1 is a rear, left, and top perspective view of a camera embodying our new design;

FIG. 2 is a left side view thereof;

FIG. 3 is a right side view thereof;

FIG. 4 is a top plan view thereof;

FIG. 5 is a bottom plan view thereof;

FIG. 6 is a front elevational view thereof;

FIG. 7 is a rear elevational view thereof; and,

FIG. 8 is a front, right, and bottom perspective view thereof; and,

FIG. 9 is a front, right, and bottom perspective view thereof illustrating the camera without a lens cover.

The broken lines in the figures are for the purpose of illustrating portions of the camera that form no part of the claimed design.

1 Claim, 9 Drawing Sheets
